UNITED STATES PATENT OFFICE.

BENJAMIN RAY THOMAS, OF SIOUX CITY, IOWA.

WRINGER.

Application filed February 18, 1926. Serial No. 29,072.

My invention relates to clothes wringers, and it is my object to provide a wringer which is so constructed that the hands of the operator can not become caught between the rolls thereof.

A further object of my invention is to provide a wringer which will wring clothes having buttons without tearing the buttons therefrom, or breaking them.

10 My invention further has for its object to provide a wringer in which the clothes can not become wound about the rolls when passing therebetween.

15 A further object of the invention is to provide a wringer in which the necessity for the ordinary rubber rolls is done away with.

A still further object of my invention is to provide such a wringer of simple, durable and inexpensive construction.

20 With these and other objects in view, my invention consists in the construction, arrangement and combination of the various parts of my device, whereby the objects contemplated are attained, as hereinafter more 25 fully set forth, pointed out in my claims and illustrated in the accompanying drawings, in which:

Fig. 1 is an elevation of a wringer embodying my invention.

30 Fig. 2 is a vertical sectional view of the same, taken on the line 2—2 of Fig. 1.

Fig. 3 is a detail sectional view, taken on the line 3—3 of Fig. 1.

Fig. 4 is a view of one of the compression 35 rolls.

Fig. 5 is a view of a slightly modified form of the compression roll.

Fig. 6 illustrates a modified form of my invention applied to an old wooden type 40 wringer.

Fig. 7 is a vertical sectional view taken on the line 7—7 of Fig. 6.

Attempts have been made to remedy the defect in the ordinary wringer, which is 45 the liability of the operator's hand becoming caught between the rolls thereof.

In solving the problem thus existing, I have proceeded with the idea that if the wringer rolls could be so mounted that they 50 would readily move apart a considerable distance under the influence of comparatively light pressure, that it would be possible for the fingers of an operator to come into contact simultaneously with the meeting surfaces of the rolls, and that the slight pressure exerted against the finger of the opera-

tor would thus cause him to jerk his hand back involuntarily, and to thereby free his hand from between the rolls.

In Fig. 1 I have shown a metallic wringer frame having side posts, 10, and connecting arch, 11. The compression rolls, 12, are mounted in the same manner as the ordinary wringer rolls, the upper roll being adjustable toward the lower roll by means of hand screws, 13. Since this construction is old in the art, it is not thought necessary to further describe or illustrate the same. The rolls, 12 (see Fig. 5) are provided with flanges, 14.

The side faces of the posts, 10, are flattened, as shown in Fig. 2, and are channeled, as at 15, the channels extending vertically thereof. The receiving rolls, 16, are provided at their ends with rollers, 17, journaled thereon by means of ball bearings, 18. Thus, the rolls, 16, are free to turn in the rollers, 17, and yet are held against longitudinal movement, the hub, 19, which forms a ball-race for the bearings, 18, being secured to the rolls, 16, as at 20. The construction just described may be provided in the form of an ordinary ball bearing.

The rollers, 17, are received in the channels, 15, and the rollers of the lower roll are supported on projecting lugs, 21, in the lower ends of the channels.

A set of rolls, 16, is provided for each side of the wringer and they are connected and held in place by means of endless belts, 22, of rubber or the like. The rolls, 12, are received inside of the respective belts, 22, and by adjusting the rolls toward each other with the hand screws, 13, the belts may be compressed together intermediate their ends. 25 As the clothes are fed into the wringer between the belts the weight of the upper belt acting against the lower belt will produce enough traction to feed the clothes between the belts. As the clothes approach the rolls, 12, the pressure between the belts will be increased, and upon passing between the rolls the water will be wrung therefrom and caused to flow rearwardly between the belts. As the clothes are fed into the wringer the upper roll, 16, is free to move upwardly, the rollers, 17, traveling in the channels, 15.

The object in slanting the faces of the posts, 10, is to enable the roll, 16, to move upwardly, as indicated in dotted lines in Fig. 4, without stretching the upper belt. An arc of a circle described by any point

along the axis of the upper roll, 16, about the upper roll, 12, as a center, will not approach the side face of the post, 10, in an upward direction until the roll, 16, has moved upwardly a considerable distance, that is, the inclination of the faces of the posts is such that these faces will be inclined upwardly and inwardly within a plane normal to the common plane of the axis of the upper 10 receiving and compression rolls. Thus, the only pressure between the belts during a certain limit of motion of the roll, 16, is the weight of the roller and the belt and the tension on the belts.

15 Should the operator catch his fingers between the rolls, 16, there will be sufficient pressure caused by such weight to induce him to react by drawing his hand away from the wringer, although the rolls may be 20 traveling at a considerable speed, and his fingers may have penetrated considerably between the rolls, he may still be able to withdraw them without difficulty.

Buttons on the clothes being fed through 25 the wringer, even though they should enter the wringer in a vertical position, will be caused to lie flat by the pressure between the belts before they reach the rolls, 12.

It is understood that the snapping of buttons in the ordinary wringer is due to the 30 buttons becoming wedged between the rolls in a vertical position transverse to the direction of motion of the clothes through the rolls. Since the faces of the rolls which 35 engage the buttons are not parallel to the line of motion of the clothes, there is little tendency in the ordinary wringer to cause the buttons to lie flat, but where they are carried a considerable distance between two 40 parallel faces, pressing against each other, the pressure will turn the buttons in one direction or the other and cause them to lie flat.

Should clothes adhere to either of the 45 belts, they will be simply carried back toward the operator by the broad faces thereof, and, having been straightened out, will not bend again so as to reenter the rolls. Wrapping in the ordinary wringer takes 50 place because the clothes will encircle the roll before the operator has a chance to prevent re-entrance.

The rolls, 12, shown in Figs. 1 and 2, are 55 preferably made of solid metal, but in some instances it may be desirable to cover the rolls with a narrow layer of rubber, as shown at 23 in Fig. 6.

The invention can be applied as an attachment to an old style wringer such as is 60 shown in Figs. 7 and 8, the channels, 15, being formed in castings, 24, which are secured to the faces of the posts, 10^a.

The belts, 22^a, used with such an attachment are of much thinner material than 65 those shown in Figs. 1, 2 and 4, since the

rubber rolls, 25, of the wringer are allowed to remain and the belts simply inserted around them. The thinness of the belts used with the steel rollers, 12, must be such as to give the required resiliency of contact 70 against the clothes, but the rubber rolls, 25, will supply that resiliency where the invention is used as an attachment, and the belts need to be only thick enough to stand the wear and strain to which they are subjected. 75

The lugs, 21^a, corresponding to the lugs, 21, of Figs. 1 and 2, are formed as part of the casting, 24.

In the preferred form of my invention, shown in Figs. 1 and 2, I employ the casing, 80 26, having ears, 27, pivoted to the lugs, 21. The casings, 26, serve to protect the rollers, 18, from dust, and are secured in closed position by means of screws, 28. The inner sides of the casings, 26, are slotted, as at 85 31, to receive the rolls, 16.

The rolls, 16^a, in the modified form shown in Figs. 7 and 8, which correspond to the rolls, 16, of Figs. 1 and 2, are provided with flanges, 32, to position the belts, since it 90 would be impractical to put the flanges on the rollers, 25.

Some changes may be made in the construction and arrangement of the parts of my invention without departing from the 95 real spirit and purpose of my invention, and it is my intention to cover by my claims any modified forms of structure or use of mechanical equivalents which may be reasonably included within their scope. 100

I claim as my invention:

1. In a wringer, a pair of side posts, compression rollers mounted in said posts and adjustable toward each other, receiving rolls spaced laterally from said compression rolls 105 and provided with rollers engaging the faces of said posts to allow said receiving rolls to move apart freely, and endless belts of compressible material supported upon said receiving rolls to travel therearound, said 110 endless belts having coacting opposed portions received between the compression rolls and adapted to be compressed therebetween.

2. In a wringer, a pair of posts having longitudinal channels in the sides thereof, a pair of compression rolls supported in said sides and adjustable toward each other, receiving rolls spaced laterally from said compression rolls, rollers journaled on the ends of said receiving rolls and received in said channels so as to allow free movement of the receiving rolls away from each other, and endless belts of compressible material supported on said receiving rolls to travel therearound, said belts having coacting opposed portions received between the compression rolls and adapted to be compressed 120 125 thereby.

3. In a wringer, a pair of posts having upwardly and inwardly inclined channels 130

on the sides thereof, compression rolls mounted in said posts and adjustable toward each other, receiving rolls spaced laterally from said compression rolls, rollers 5 journaled on the ends of said receiving rolls and received in said channels, and a pair of endless belts of compressible material supported upon said receiving rolls and having co-acting opposed portions received 10 between the compression rolls and adapted to be compressed thereby.

4. In a wringer, a frame, a pair of compression rolls mounted in said frame, a pair of receiving rolls spaced laterally from said 15 compression rolls, the upper of said receiving rolls having end portions rollably engaged against said frame for upward movement away from the lower of said receiving

rolls, the surfaces of the frame engaged by said end portions being inclined inwardly 20 and upwardly within a plane normal to the common plane of the axes of the upper receiving roll and the upper compression roll, and endless belts of compressible material supported to travel between said receiving 25 and compression rolls in such manner as to provide extending coacting belt portions, the extremity of said portions between the receiving rolls resting normally in contact with each other without pressure between 30 the receiving rolls.

Signed at Sioux City, in the county of Woodbury and State of Iowa, this 10 day of February, 1926.

BENJAMIN RAY THOMAS.
